UNITED STATES PATENT OFFICE.

MOSSIMO LOTTI, OF NORTH MILWAUKEE, WISCONSIN.

DESIGN FOR A COMBINATION LAMP AND SMOKER'S STAND.

Application filed November 12, 1928. Serial No. 28,852. Term of patent 7 years.

To all whom it may concern:

Be it known that I, MOSSIMO LOTTI, a subject of the King of Italy, and resident of North Milwaukee, in the county of Milwaukee and State of Wisconsin, whose post-office address is 8 North Milwaukee Avenue, North Milwaukee, Wisconsin, have invented a new, original, and ornamental Design for a Combination Lamp and Smoker's Stand, of which the following is a description, reference being had to the accompanying drawing, forming part thereof.

In the drawing, the figure is a perspective view of the combination lamp and smoker's stand.

I claim:

The ornamental design for a combination lamp and smoker's stand, as shown.

MOSSIMO LOTTI.
